Primary Examiner—Gary D. Watson[57] **CLAIM**

The ornamental design for an ultimate bleacher seat, as shown and described.

DESCRIPTION

FIG. 1 is a front elevational view of the ultimate bleacher seat showing my new design;

FIG. 2 is a rear elevational view thereof;

FIG. 3 is a right view thereof;

FIG. 4 is a top plan view thereof;

FIG. 5 is a bottom plan view thereof; and,

FIG. 6 is an isometric view thereof.

The schematic depiction of mesh-like fabric on the seat and backrest is understood to be continuous throughout. FIG. 6 has been shown on an enlarged scale with respect to FIGS. 1 through 5.
